STENCILING APPARATUS

Jakob Dichter, Berlin-Schoneberg, Germany

Application September 6, 1938, Serial No. 228,640
In Germany September 18, 1937

3 Claims. (Cl. 101—114)

The present invention relates to the application of colored inscriptions and designs to glass, ceramic or similar smooth, non-absorptive surfaces. More particularly, the invention pertains to a method and apparatus for stenciling letters, designs, or other markings on the ware.

In previous methods of applying fluid fusible colors to glass and ceramic ware, it has been found difficult to apply a sufficient quantity of the coloring material to provide satisfactory adhesion thereof unless expensive or time-consuming steps are employed.

One of the objects of the invention is to apply the coloring material to the ware through a stencil and in such a manner that sufficient pressure is exerted on the coloring material to produce a clear outline.

Another object of the invention is to apply the pressure to the fluid through the medium of the ware to which the colors are to be applied.

Other objects will be apparent from the following description thereof taken with the accompanying drawing, in which:

Fig. 1 is a sectional front elevation illustrating diagrammatically one type of apparatus for carrying out the method herein described; and

Fig. 2 is a fragmentary section through the stencil.

In the drawing, a receptacle 10, designed to hold a quantity of a semi-fluid coloring material, consists of two parts 11 and 12, the former being telescopically slidable in the lower part 12. Suitable packing 13 is interposed between the walls of these parts to prevent leakage from the receptacle. It will be seen that the lower section 12 is open only at its upper end, while the upper section 11 is open at each end thereof, the upper end 14 being reduced to form a mouth over which the stencil 15 may be secured by suitable clamping means 16. The stencil is that type in which a meshed silk fabric 17 is provided with a coating of gelatin or similar material 18, the outline of the design or lettering being formed by cutting away the gelatin as indicated by openings 19.

If desired, the receptacle 10 may be connected with a supply reservoir 20 containing coloring material under constant pressure supplied by the weighted piston 21. The receptacles 10 and 20 are connected by means of a suitable conduit 22. The weight of the piston 21 is such that it will exert a pressure within the receptacle 10 insufficient to force the coloring material through the stencil, but sufficient to maintain a full supply of coloring material in the receptacle 10 at all times. The method of employing the apparatus just

described consists in completely filling the receptacle with coloring material and then fixing the stencil, having a suitable design or pattern cut from its gelatin coating, over the upper open end or mouth of the receptacle 10. The supply of coloring material within the receptacle completely fills the receptacle, but the pressure thereon is insufficient to force it through the screen. If, however, additional pressure is placed on the top of the slidable section 11, as for instance by properly positioning the ware against the screen and exerting a downward pressure thereon, the coloring material will be forced through the screen onto the ware. This pressure is maintained until a sufficient quantity of the coloring material has been forced through the screen and adheres to the ware. The quantity of coloring material is, of course, governed by the pressure exerted and the duration of the pressure. Since the gelatin coating is impervious, the coloring material will be forced through that portion of the screen only from which the coating has been removed.

While the drawing of the apparatus is more or less diagrammatic, it is intended that the device shown be used for hand operation as well as in automatic machines. In many types of automatic machinery for making glass articles, such for example as vials or bulbs which are shaped from glass tubing, large quantities of these articles may be produced at a relatively low cost. In machines of this type, it is apparent that a modified form of apparatus embodying the principles of that shown in the drawing may be made an auxiliary part of the automatic machine and the articles provided with color markings before they leave the machine. It is obvious that the use of such a device will reduce the cost of making and coloring the articles. When the articles are cylindrical or prismatic in form, they may be rolled over the stencil and at the same time sufficient pressure is exerted during the rolling operation to transfer the necessary quantity of color to the article.

The receptacle may consist only of the telescoping parts 11 and 12, but since it is desirable that the screen be supplied continuously with a coloring material, the reservoir 20 is preferably used in connection with the container to which the transfer stencil is attached. It is evident that by using a reservoir in connection with the transfer receptacle, it will not be necessary to disassemble the telescoping parts of the latter to fill the same with a fresh supply of coloring material. It is only necessary that the reservoir be

periodically refilled or further supplied with the fluid coloring material to maintain a sufficient quantity of the material in the transfer receptacle at all times.

5 While a preferred form of apparatus has been described and the method of using the same has been set forth in detail, it is not intended that the present invention be limited to the exact details or steps referred to herein.

10 What is claimed is:

1. In an apparatus for applying fluid coloring material to glass and similar ware, a receptacle for holding the material comprising a pair of hollow members, one telescoped within the other 15 and relatively movable thereto, said one member having an open mouth, a stencil secured to said one member over said mouth, and means for imposing a pressure on the material in said receptacle to force the material against the stencil but insufficient to force the material through the stencil.

2. In an apparatus for applying fluid coloring material to glass and similar ware, a receptacle for holding the material comprising a pair of hollow members, one telescoped within the other 20 and relatively movable thereto, said one member having an open mouth, a stencil secured to said

one member over said mouth, a second receptacle communicating with said first-mentioned receptacle and adapted to supply material to the first-mentioned receptacle, and means in said second receptacle for imposing a pressure on the material in said receptacles sufficient to force the material against the stencil but insufficient to force the material through the stencil. 5

3. In an apparatus for applying fluid coloring material to glass and similar ware, a receptacle 10 for holding the material comprising a pair of cylindrical shells, one telescopically and vertically slidable within the other, said one shell being open at each end thereof and having a stencil secured over the upper open end thereof, 15 a second receptacle communicating with said first-mentioned receptacle and adapted to supply material to the first-mentioned receptacle, a weighted piston in said second receptacle for imposing a pressure on the material in both of 20 said receptacles sufficient to force the material against the stencil but insufficient to force the material through the stencil, said one shell being movable when external downward pressure is imposed thereon to force the material through the 25 stencil.
